US00D905257S

(12) **United States Design Patent** (10) **Patent No.:** **US D905,257 S**
Harmon et al. (45) **Date of Patent:** **** Dec. 15, 2020**

(54) **JOINT STABILIZATION SOCK**

- (71) Applicant: **Better Walk, Inc.**, Atlanta, GA (US)
(72) Inventors: **Tyler Jack Prescott Harmon**, Decatur, GA (US); **Partha Sarathy Unnava**, Atlanta, GA (US); **Pranav Chunduri**, Cary, NC (US)
(73) Assignee: **BETTER WALK, INC.**, Atlanta, GA (US)
(**) Term: **15 Years**
(21) Appl. No.: **29/730,627**
(22) Filed: **Apr. 7, 2020**

CLAIM

The ornamental design for a joint stabilization sock, as shown and described.

DESCRIPTION

FIG. 1 is a perspective view of an exemplary joint stabilization sock;

FIG. 2 is a front view of an exemplary joint stabilization sock;

FIG. 3 is a rear view of an exemplary joint stabilization sock;

FIG. 4 is a right side view of an exemplary joint stabilization sock;

FIG. 5 is a left side view of an exemplary joint stabilization sock;

FIG. 6 is a top view of an exemplary joint stabilization sock; and,

FIG. 7 is a bottom view of an exemplary joint stabilization sock.

The broken lines in the drawings are for the purpose of illustrating portions of the joint stabilization sock and form no part of the claimed design.

1 Claim, 7 Drawing Sheets
